UNITED STATES PATENT OFFICE.

ELMER A. HERBST, OF STURGEON BAY, WISCONSIN.

IRONING TABLE.

Application filed July 5, 1922. Serial No. 572,881.

To all whom it may concern:

Be it known that I, ELMER A. HERBST, a citizen of the United States, residing at Sturgeon Bay, in the county of Door and State of Wisconsin, have invented certain new and useful Improvements in an Ironing Table; and I do hereby declare the following to be a full, clear, and exact description of the invention, such as will enable others skilled in the art to which it appertains to make and use the same.

This invention relates to a table particularly adapted for use in the laundry or home as for ironing purposes.

15 It is aimed to provide a collapsible construction employing novel features enabling the same to be moved to either an open or closed position by one hand of the user.

A second object is to provide a novel construction which will automatically open or close through movement initially imparted as to the board thereof, respectively adjacent opposite ends thereof for the folding and unfolding movements.

25 Still another object is to provide a construction utilizing a top or board, a foldable pedestal therefor, foldable prop means therefor and coacting struts, one hinged to the top means and one slip-connected to the board and both slip-connected to the pedestal.

Additional objects and advantages will become apparent from a consideration of the description following taken in connection with accompanying drawings illustrating one practical embodiment.

In said drawings:—

Figure 1 is a side elevation showing the table unfolded;

40 Figure 2 is a side elevation thereof but showing it folded;

Figure 3 is a central longitudinal vertical sectional view showing the parts in partly collapsed or folded condition;

45 Figure 4 is an end elevation;

Figure 5 is a detail perspective view illustrating the connection of the props to the pedestal;

50 Figure 6 is an inverted plan view of the table folded;

Figure 7 is a fragmentary detail plan view of the slip connection of the board and coacting strut;

55 Figure 8 is a detail perspective view illustrating the movable plate connection for the struts.

Like reference characters designate like or similar parts in the different views.

In reducing the invention to practice, a top or board is provided as at 10 of any suitable material, size or shape, preferably being of the usual shape and reduced at its forward end as at 10^a as usual. A pedestal is employed, being generally designated 11 and of any suitable construction, employing 60 for instance legs 12. Two of such legs are shown which are rigidly connected together by means of transverse bars 13. Rigidly secured to the undersurface of the board 10 are cleats 14 loosely or rigidly mounting a 65 pivot rod 15 and which extends through the legs 12 as shown in order to pivotally mount the legs and pedestal for folding movement 70 against the board 10.

A suitable prop means also foldable 75 against the board 10 is provided as at 16 and may consist of two prop bars 17 pivotally mounted at their upper ends on the rod 15. Said bars 17 diverge upwardly and intermediate their ends have a brace bar as at 80 18 fastened thereto.

Struts 19 and 20 are also utilized, which are foldable against the board 10. The strut 19 has one end disposed intermediate the props 17 and pivoted thereto as by means of 85 a bolt or rod 21. Suitably fastened parallel to the legs 12 and to the bars 13 are guide strips 22, preferably being four in number and spaced apart so as to provide a way at 23. Slidable in the way 23 is a leaf or plate 90 24 having pins 25 and 26 thereon on each end of which a roller 27 is journaled and adapted to directly engage the strips 22 in order to reduce friction incidental to travel 95 of the leaf or plate. The strut 19 at one end is pivotally connected to the pin 25, passing intermediate the adjacent strips 22. On the other hand, strut 20 is pivoted to the pin 26, passing intermediate the same strips 22 as the strut 19. Strut 20 is disposed intermediate the prop 17 and below the brace bar 18 as shown and is supported and guided by 100 a guide rod 18^a pivoted in the props 17, being disposed intermediate bar 18 and rod 18^a and loosely resting in a loop 18^b of the rod. Said strut 20 at its upper end as at 28 is engaged with the under surface of the board 10 so that it may move into and out of abutment with a transverse cleat or stop 105 29 secured to the under surface of said board 10. In order to hold the parts against accidental unfolding when in a collapsed or

folded condition, a hook 30 may be suitably provided as on one of the bars 13 for separable engagement with an eyelet 31 provided for instance on the cleat 29.

5 The legs 12 and prop 17 are connected preferably on opposite sides of the cleat 14 and the props 17 are of such length as to extend beyond and be free of the struts 19 and 20 when the parts are in a folded condition 10 and as particularly shown in Figure 6.

It will be seen that when the table is in an operative or unfolded position, the top 10 is horizontal and rigidly supported by the pedestal, prop 17 and struts 19 and 20, as the 15 latter has its upper end in abutment with the stop or cleat 29. It will be noted that the end 11 of the table is unrestricted for a considerable distance below it so that dresses or other tubular articles may be readily penetrated by said end. In order to fold the table, it is simply necessary to depress the top 10 by one hand at its widest or pedestal end which will elevate the cleat 29 above and 20 out of engagement with the strut 20 whereupon the top 10 will move downwardly causing the struts 19 and 20, pedestal 11 and prop 16 to collapse or fold to the position shown in Figure 2. In this position, the parts occupy minimum space which is 25 advantageous from the standpoint of shipment and also of the room occupied in a house or building when the article is not in use. In order to secure the parts against accidental unfolding from such position, the 30 hook 30 and eyelet 31 may be engaged. In order to unfold the table, the parts 30 and 35 31 are disengaged and the top 10 engaged by one hand adjacent its smaller end 10^a and elevated, thus causing the strut 20 to move 40 along the under surface of the table top 10 resulting in unfolding of the pedestal 11 and props 17, and finally engaging behind the cleat 29 so that the parts will thus be in rigid relation. It is clear of course that in- 45 cidental to the folding and unfolding of the table that the plate 24 slides in the way 23 so as to provide for folding and unfolding movement of the struts 19 and 20 and of the pedestal.

50 As merely one practical embodiment has been illustrated and described, it is to be understood that changes in the details may be resorted to provided they fall within the spirit and scope of the invention.

55 I claim as my invention:—

1. A collapsible table having a board, a

pedestal pivotally connected thereto and provided with a way, a prop pivotally connected to the board and to the pedestal, a strut adjacent one end pivoted to the prop, a second strut at one end being adapted for abutment with the board, and the other ends of the struts being disposed and slidable in said way.

2. A collapsible table having a board, a pedestal foldably connected thereto and provided with a way, a plate slidable in said way, a prop pivotally connected to the pedestal and board, a strut formed at one end for abutting contact with the board to prevent collapse thereof, a strut pivotally connected to the prop adjacent one end, and the other ends of the struts being pivotally connected to said plate.

3. A collapsible table consisting of a board, a pedestal pivotally connected thereto, a prop foldably connected to the board; a strut pivotally connected to the prop, a strut normally abutting and being disengageable from the board, means slip-connecting both struts to the pedestal for travel of said struts at the adjacent ends substantially longitudinally of the pedestal, and abutment means coacting with the second mentioned strut to prevent accidental collapse of the table in unfolded position.

4. A collapsible table consisting of a board, a pedestal, said pedestal having spaced strips providing a way, a plate slid- 90 able in said way, upwardly diverging prop bars, a cleat on the board, a rod passing through the pedestal, prop bars and cleat to pivotally connect said pedestal and prop bars to the board, a strut having one end disposed intermediate the prop bars adjacent the lower ends thereof, a pivot member passing through said prop bars and said strut, a second strut, said second strut passing intermediate the prop bars and being disengageable with the board, a guide rod 100 on the prop bars for the second strut, abutment means on the board to coact with the second strut to hold the table in an unfolded condition, said struts passing intermediate said strips, and means pivotally connecting 105 said struts to the plate.

In testimony whereof I affix my signature in presence of two witnesses.

ELMER A. HERBST.
